UNITED STATES PATENT OFFICE

165,183

CLOTHES-WASHING MACHINE

Joseph R. Mango, Chicago, Ill., assignor to Thor Corporation, Chicago, Ill., a corporation of Illinois

Application October 30, 1950, Serial No. 12,779

Term of patent 14 years

(Cl. D49—1)

To all whom it may concern:

Be it known that I, Joseph R. Mango, a citizen of the United States, residing at Chicago, in the county of Cook and State of Illinois, have invented a new, original, and ornamental Design for a Clothes-Washing Machine, of which the following is a specification, reference being had to the accompanying drawing, forming a part thereof.

In the drawing:

I claim:

The ornamental design for a clothes-washing machine, substantially as shown.

JOSEPH R. MANGO.
